UNITED STATES PATENT OFFICE

SALVATORE J. LA SUSA AND WILLIAM SAMBUR, OF JAMAICA, NEW YORK

DESIGN FOR A KITCHEN CABINET

Application filed December 9, 1932. Serial No. 46,410. Term of patent 3½ years.

To all whom it may concern:

Be it known that we, SALVATORE J. LA SUSA and WILLIAM SAMBUR, citizens of the United States, residing at Jamaica, in the county of Queens and State of New York, have invented a new, original, and ornamental Design for Kitchen Cabinets, of which the following is a specification, reference being had to the accompanying drawing, forming part thereof.

The figure is a perspective view of a kitchen cabinet, showing our new design.

We claim:

The ornamental design for a kitchen cabinet, as shown.

SALVATORE J. LA SUSA.
WILLIAM SAMBUR.
